UNITED STATES PATENT OFFICE.

JAMES SLOAN ADAMS, OF NEW YORK, N. Y.

PROPELLING MEANS FOR AEROPLANES.

1,356,329.

Specification of Letters Patent. Patented Oct. 19, 1920.

Application filed August 27, 1918. Serial No. 251,663.

To all whom it may concern:

Be it known that I, JAMES SLOAN ADAMS, a citizen of the United States, and a resident of the city of New York, borough of 5 Manhattan, in the county and State of New York, have invented a new and Improved Propelling Means for Aeroplanes, of which the following is a full, clear, and exact description.

10 The object of the invention is to provide a new and improved propelling means for aeroplanes and similar craft, arranged to utilize the stored-up energy of a spring to the fullest advantage for driving the aero- 15 plane forward. Another object is to dispense entirely with the propelling wheel now generally employed and to use instead a spring, and a resistance plane connected with the spring, the latter being compressed 20 during the power stroke of a motor and suddenly released during the exhaust stroke to utilize the stored up energy of the compressed spring to give a forward propelling impulse to the aeroplane. Another object is 25 to utilize the motor for compressing the spring during the power stroke and suddenly releasing it on opening the exhaust valves.

With these and other objects in view, the 30 invention consists of certain novel features of construction, as hereinafter shown and described and then specifically pointed out in the claims.

A practical embodiment of the invention 35 is represented in the accompanying drawings forming a part of this specification, in which similar characters of reference indicate corresponding parts in all the views.

Figure 1 is a sectional plan view of an 40 aeroplane provided with the improved propelling means, the section being on the line 1—1 of Fig. 2;

Fig. 2 is a front elevation of the same;

Fig. 3 is an enlarged sectional side elevation of the same on the line 3—3 of Fig. 1; and

Fig. 4 is an enlarged sectional plan view of the motor and the spring.

The aeroplane shown in the drawings and 50 on which the propelling means is shown, is in the form of a biplane having the usual framework 10, top and bottom sustaining planes 11 and 12 and the carriage 13. In the carriage 13 is mounted a motor 20, preferably in the form of a two-cycle internal combustion engine having a cylinder 21, the

axis of which extends lengthwise of the aeroplane, as plainly indicated in the drawings. In the cylinder 21 reciprocates a piston 22 provided with a forwardly extending piston rod 23 on which is secured a cross-head 24 engaging the rear end of a powerful coil spring 25 resting with its forward end on a plate 26 adjustably mounted on rods 27 attached to the forward head 28 of the cylinder 21. Nuts 29 screw on the rods 27 and serve to adjust the plate 26 in a lengthwise direction to adjust the tension of the spring 25 correspondingly. When the motor is running then the spring 25 is compressed during the power stroke, that is during the time the piston 22 is moved forward and with it the crosshead 24, and when the piston 22 is on the exhaust return stroke then the compressed spring 25 is suddenly released and its stored up energy is utilized for imparting a powerful forward propelling impulse to the aeroplane. As shown in Fig. 4, the forward end of the cylinder 21 is provided with the usual inlet 30 for passing an explosive mixture into the forward end of the cylinder 21 and this explosive mixture is compressed during the forward stroke of the piston 22 and is forced through a pipe 31 and past the valve 32 into a reservoir 33 connected by a pipe 34 and inlet valve 35 with the rear or working chamber end of the engine. This rear end of the cylinder 21 is provided with the usual igniting device 36 and with an exhaust valve 37 connected with an exhaust pipe 38 for carrying off the exhaust gases. The admission valve 35 and the exhaust valve 37 are controlled by the usual mechanisms 39 and 40 actuated from the engine shaft 41 connected by a pitman 42 with the forward end of the piston rod 23. Fly wheels 44 are mounted on the shaft 41 to insure uniform running of the engine.

Intermediate the sustaining planes 11 and 12 are arranged resistance planes 50 and 51 located on opposite sides of the carriage 13. Each of the resistance planes 50 and 51 is connected with the crosshead 24 to move the resistance planes 50 and 51 slowly upward during the forward movement of the piston 22 and crosshead 24, and very fast downward during the return movement of the said piston 22 and crosshead 24. For the purpose mentioned the sides of each resistance plane 50 and 51 are provided with bearings 52 mounted to slide up and down

on vertical posts 53 forming part of the frame 10 of the aeroplane. The crosshead 24 is connected by cords, cables or similar flexible connections 60 and 61 with the sides 5 of the resistance planes 50 and 51 to alternately raise and lower the latter during the running of the engine. The flexible connections 60 and 61 after leaving the crosshead 24 pass around suitable guide pulleys 62, 63 and 64 to impart the desired movement to the resistance planes 50 and 51 during the running of the engine.

The operation is as follows:

When the engine is running and the piston 15 ton 22 is on the forward or power stroke then the crosshead 24 compresses the spring 25 and pulls the resistance planes 50 and 51 in an upward direction. When the piston 22 has reached the end of its forward stroke 20 and the exhaust valve 37 is opened then a quick return movement is had by the action of the stored up energy of the compressed spring 25 and a sudden downward movement is given to the resistance planes. 25 Owing to the fact that upon the compression of the spring 25, the forward edge of each of the resistance planes is elevated, it will be apparent that said planes will assume an angular position with relation to the sustaining planes, and when under the influence 30 of the stored energy of said spring they are again returned to the horizontal, the action gives a forward movement to the aeroplane. It will be noticed that when the spring 25 is released on opening the exhaust valve 37 then the stored up energy in the spring acting 35 on the fixed plate 26 gives a forward propelling impulse to the aeroplane. It will further be noticed that the resistance 40 of the air against the resistance planes 50 and 51 in their up and down motion causes the stored up energy in the spring to be exerted in a forward direction against the aeroplane to drive the latter forward. The 45 resistance of the air against the resistance planes 50 and 51 in their up and down movement counteracts on the rebound in the spring 25 and causes the aeroplane to be forced forward by the stored up energy in the 50 spring.

The resistance planes 50 and 51 are practically parallel to the sustaining planes 11 and 12 to maintain the aeroplane in equilibrium.

55 The weight of the planes 50 and 51 and that of the piston and piston rod relative to the power developed by the burning mixture counteracts on the rebound of the spring and therefore adds to the driving power of the spring to propel the aeroplane forward.

Having thus described my invention, I

claim as new and desire to secure by Letters Patent:—

1. In an aeroplane and like craft, a resistance plane, a spring arranged lengthwise of the machine and connected with the said resistance plane, and means for alternately compressing and suddenly releasing the compressed spring to actuate the said resistance plane and to give a forward propelling impulse to the aeroplane. 70

2. In an aeroplane and like craft, spaced sustaining planes, a resistance plane movable intermediate the said sustaining planes, 75 a spring arranged lengthwise of the aeroplane and connected with the said resistance plane, and a motor connected with the said spring to alternately compress and release the spring, the latter imparting movement 80 to the resistance plane in one direction during the power stroke and a sudden movement to the plane in the opposite direction on the spring being released to utilize a portion of the stored up energy of the spring 85 to give a forward propelling impulse to the aeroplane.

3. In an aeroplane and like craft, spaced sustaining planes, a resistance plane movable intermediate the said sustaining planes, 90 a spring arranged lengthwise of the aeroplane and connected with the said resistance plane, and a motor connected with the said spring to compress the latter on the power stroke of the motor and move the resistance 95 plane in one direction, and to suddenly release the compressed spring on the exhaust stroke of the motor to move the resistance plane suddenly in an opposite direction to give a forward propelling impulse to the 100 aeroplane.

4. In an aeroplane and like craft, spaced sustaining planes, a resistance plane intermediate the said sustaining planes and mounted to move up and down, a motor 105 mounted on the aeroplane and having its axis lengthwise of the aeroplane, the motor having a reciprocating piston provided with a piston rod, a coil spring connected at one end with the said piston rod and having its 110 other end fixed forward of the motor, the axis of the spring extending lengthwise of the aeroplane, the spring being compressed on the power stroke of the engine and released on the exhaust stroke of the engine, 115 and a flexible connection between the piston rod and the said resistance plane to move the latter in one direction during the power stroke of the engine and in the opposite direction during the exhaust stroke to utilize 120 the stored up energy of the spring for giving a forward propelling impulse to the aeroplane.

JAMES SLOAN ADAMS.
